UNITED STATES PATENT OFFICE.

JAMES V. FISHER, OF SALEM, OHIO.

HARNESS-HOOK.

1,163,649.

Specification of Letters Patent. Patented Dec. 14, 1915.

Application filed May 13, 1913. Serial No. 767,364.

To all whom it may concern:

Be it known that I, JAMES V. FISHER, citizen of the United States, residing at Salem, in the county of Columbiana and State of Ohio, have invented certain new and useful Improvements in Harness-Hooks, of which the following is a specification.

This invention relates to improvements in harness, and more particularly to a specially devised hook adapted to be used as a check-rein fastening device.

The primary object of the invention contemplates the provision of a simple and inexpensive harness hook or device wherein means is provided for detachably fastening the check-rein to the saddle in such a novel and peculiar manner as to permit an unfastening of the former by simply swinging the attaching hook and its retaining element upon the pivotal support provided therefor, the retaining element being swung or moved until the said hook registers or is aligned with a peculiarly shaped cut out portion formed within a detachable supporting bracket carried by the saddle, whereupon the said hook is laterally slid until entirely free of the retaining element, this operation effecting a convenient and reliable check-rein hook capable of being manufactured and placed upon the market at a minimum cost.

A further object of the invention resides in the provision of a concentrically pivoted cam within which the hook member is normally retained, the latter having a projection or tongue adapted to fit into a cut out portion formed within the said cam, wherein it is retained against accidental removal by the bracket or support upon which the

cam is pivoted.

A still further object of the invention contemplates the provision of check-rein fastening means of such simple construction as to be readily attached to any of the well known harness saddles now in use, the arrangement comprising the invention permitting the check-rein to be quickly detached from the retaining means as occasion demands.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:—

Figure 1 is a side elevation, illustrating the application of the invention; Fig. 2 is a side elevation of the fastening device; Fig. 3 is an end view; Fig. 4 is a section on line 4—4 of Fig. 2; and Fig. 5 is an end view, partly broken away, the hook member being positioned ready for removal or detachment from the retaining means.

Before proceeding with the description of the drawings, I desire to call particular attention to the fact that while I have evolved my invention with particular reference to its application as a check-rein fastening device, the same may be readily utilized as a trace hook, or for any other purpose susceptible of its application.

Referring now to the drawings wherein is illustrated the preferred form of my invention the numeral 1 designates a harness saddle of the ordinary type and 2 an ordinary form of check-rein.

Detachably secured to the saddle 1 by means of an exteriorly threaded shank or stem 3 is the supporting bracket 4 of the fastening device, the lower face of which is concaved as at 5 to conform to the curvature or outline of the saddle 1, the said bracket having extensions or sides 6 formed integrally therewith and between which a concentrically pivoted cam 7 forming the retaining element of the device is supported through the medium of a pin 8 extending through the said cam and the sides 6 of the supporting bracket.

A peculiarly shaped cut out portion 9 is formed within one of the sides 6 of the bracket the said cut out portion having an opening 10 leading thereto from one edge of the said sides, the shape of the cut out portion conforming with the shape or outline of a tongue 11 formed integrally with and projecting from one edge of the hook member 12, the latter being secured in any suitable manner to the check-rein 2 in connection with which the invention is employed. The cam or retaining element 7 is likewise provided with a longitudinally extending cut out portion or recess 13 likewise having an opening or passage way 14 leading thereto from one face of the cam, the said passage way being formed adjacent an enlargement

15 of the cam member, the purpose of which will be hereinafter fully described. By swinging the retaining element 7 until the enlargement 15 engages the base of the supporting bracket 4 as is clearly shown in Fig. 5 of the drawings, the longitudinally extending groove 13 and the cut out portion 9 of the bracket side are alined or so positioned as to register one with the other, in 10 which position the integrally formed tongue or projection 11 of the hook member 12 is free to be inserted into the groove 13 through the said cut out portion, the length of the extension or tongue being approximately the same as that of the groove so as to fit entirely within the same and allow the retaining element or cam to be swung freely upon its pivot pin 8. After inserting the hook member as above described, the latter having the check-rein attached thereto, the retaining element is swung upon its pivot drawing the enlargement 15 of the cam out of engagement with the base of the supporting bracket 4 until the hook member 12 extends forwardly from the supporting bracket or upon the same plane as the check-rein 2 where it is held in fastened position within the bracket and retaining element by the pressure brought to bear upon the check-rein. As the hook member and retaining element are swung upon the pivot provided therefor the groove 13 is thrown out of alinement with the cut out portion 9 of the bracket side, this movement of the retaining element locking the hook member therein yet permitting the said member to be freely moved without danger of accidental removal or unlocking of the said hook member.

By fastening a supporting bracket constructed as above described to each end of a swingletree and securing the harness traces to the hook members provided therefor it will be seen that the said traces may be detachably secured to the swingletree in a like manner to that described for securing or fastening the check-rein of the harness.

It will be seen from the above, taken in connection with the accompanying drawings that by disposing the cut out portion 9 of the bracket side toward the rear of the bracket the hook member cannot be withdrawn from the cam or retaining element without first swinging the latter upon its pivot until the groove formed therein registers with the said cut out portion; that the enlargement 10 of the retaining element when swung into engagement with the lower face of the supporting bracket alines the said groove and the said cut out portion, thus permitting the hook member to be removed or inserted within the groove as desired; and that the provision of the threaded shank depending from the supporting bracket the entire device may be detachably secured to the harness saddle 1 in connection

with which the check-rein fastening device comprising my invention is used.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. A harness attachment including a substantially U-shaped supporting bracket, a grooved retaining element mounted for rotation between the extensions of said bracket, one of said extensions having a slot adapted for registration with said groove, and a hook member having an extension adapted to fit the said groove, the rotation of the said element adapted to lock the said hook member, as and for the purpose set forth.

2. A harness attachment including a supporting bracket having extensions formed thereupon, a grooved retaining element mounted for rotation between said extensions, one of said extensions having a slot formed therein, an enlargement formed upon the said retaining element adapted for engagement with the said bracket to aline the said groove with the said slot, and a hook member having an extension formed integrally therewith, said extension adapted to fit the said groove of the said retaining element, the rotation of the latter adapted to lock the said hook member with the said retaining element, as and for the purpose set forth.

3. A harness attachment including a supporting bracket having extensions formed thereupon, one of said extensions having a slot formed therein, a grooved cam-shaped retaining element mounted for rotation between said extensions, the said element being adapted for engagement with the said bracket to aline the said groove with the said slot, a hook member, and an extension formed integrally therewith, the said extension being shaped similarly to the said slot and the said groove, the said extension adapted to slide laterally through the said slot and into the said groove, the latter being in registration, the rotation of the said element adapted to automatically lock the said hook member thereto, as and for the purpose set forth.

4. A harness attachment including a substantially U-shaped supporting bracket, a retaining element mounted for rotation be-

tween the sides of the said bracket, an enlargement formed upon the said retaining element adapted for engagement with the base of the said bracket, the said retaining 5 element having a groove formed therein, one of the said sides of the bracket having a slot formed therein, the said slot and the said groove adapted to be alined during engagement of the said enlargement with the base 10 of the said bracket, and a hook member having an extension adapted to fit the said groove, the rotation of the said element adapted to disaline the said groove with the said slot and to lock the said extension with 15 in the said groove, as and for the purpose set forth.

5. The combination with a U-shaped bracket of a retaining member formed with a T-shaped groove and mounted for rotation 20 between the sides of said bracket, one of which sides is provided with a T-shaped

slot for registration with said groove, upon proper movement of said retaining member, a hook member formed on one extremity with a T-shaped enlargement, of a size to 25 fit in said groove and slot, and means for limiting the rotation of said retaining member in one direction when said groove is alined with said slot to receive in the former said enlargement so that said groove and slot may be moved out of alinement in order to maintain said enlargement against lateral displacement by said bracket sides and against longitudinal displacement by said 30 groove.

35 In testimony whereof I affix my signature in presence of two witnesses.

JAMES V. FISHER.
